UNITED STATES PATENT OFFICE.

DEAN W. KING, OF SAN JOSE, CALIFORNIA.

COMBINATION TELESCOPING CLEANING-ROD FOR GUNS.

1,008,548.

Specification of Letters Patent. Patented Nov. 14, 1911.

Application filed March 8, 1910. Serial No. 548,030.

To all whom it may concern:

Be it known that I, DEAN W. KING, a citizen of the United States, residing at San Jose, county of Santa Clara, and State of California, have invented certain new and useful Improvements in Combination Telescoping Cleaning-Rods for Guns; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a cleaning rod for guns.

My improved device consists of two telescoping parts adapted to be connected by screw threads when extended to their limit of movement and when the device is employed for gun-cleaning purposes. When not in use the two members are detached by unscrewing their co-operating portions after which the one member is allowed to drop into the other, whereby the device is brought into relatively small compass and is adapted to be carried in the gun barrel when the latter is disconnected from the receiver or body of the gun.

The rear extremity of the cleaning rod is enlarged to fit the corresponding extremity of the gun barrel. Within this enlarged portion is located a screw driver and an oil can, the base of the can consisting of a milled head having a screw threaded extension adapted to connect with screw threads formed in the base of the rod. The handle of the screw driver is recessed to receive the pin connected with the nozzle of the can. The forward extremity of the rod is equipped with a washer adapted to fit closely within the barrel of the gun thus preventing the rod from rattling and at the same time serving to distribute the oil in the barrel when lubrication is necessary.

Having briefly outlined my improved construction, I will proceed to describe the same in detail, reference being made to the accompanying drawing in which is illustrated an embodiment thereof.

In this drawing: Figure 1 illustrates a gun shown in two pieces, the barrel having been detached from the body portion. In this view my improved combination cleaning rod is shown in place, being indicated for the

most part by dotted lines. Fig. 2 is a detail view of the rod shown in extended position. Fig. 3 is a fragmentary sectional view of the rear portion of the rod, showing the screw driver and oil can construction. Fig. 4 is a fragmentary view of the rod shown partly in section. Fig. 5 is a fragmentary sectional view of the forward end of the rod. Fig. 6 is a detail view of the washer and the detachable screw member upon which it is mounted. Fig. 7 is a fragmentary detail view of the forward extremity of the rod with the washer and screw removed.

The same reference characters indicate the same parts in all the views.

Let the numeral 5 designate the gun barrel and 6 the body of the gun.

My improved device consists of a cleaning rod 7 composed of two members 8 and 9, the member 8 being hollow to receive the member 9 which telescopes within the member 8 which is interiorly threaded as shown at 10 to receive the relatively short exteriorly threaded portion 12 of the part 9. When the rod is in the extended position, (see Fig. 2), it may be locked in such position by connecting the screw threaded portions 10 and 12 of the two members. When it is desired to allow the member 9 to slide into the member 8, the threaded parts 10 and 12 are disconnected. The co-operating threaded portions 10 and 12 of the two parts are so constructed that the part 9 cannot be removed from the part 8 through the forward extremity of the latter, since the threads 10 are located some distance from the forward extremity of the part 8, and the threaded portion 12 of the part 9 has a radius greater than the body of the member 9 by the depth of the screw threads 12.

The member 8 is hollow throughout its length. Its rear extremity is enlarged as shown at 13 to fit the base or rear extremity of the gun barrel. Forward of this cylindrical portion 13 the rod is tapered as shown at 14 to receive a screw driver or other tool consisting of a handle 15 and a blade or operating device 16. Within the cylinder part 13 of the rod is located an oil can 17 whose outer extremity consists of a milled head 18 having a forward threaded extension 19 screwed into the exteriorly threaded part 20 at the rear extremity of the hollow rod. The milled head 18 is of greater circumference than the hollow rod and protrudes beyond the rear extremity of the rod whereby

- it is adapted to fit the annular shoulder usually formed on the rear portion of the shell chamber of the gun accessible for the purpose of removing and attaching the oil can.
- 5 The body of the can is located within the cylindrical portion of the rod and the pin 21 at the forward end of the can enters a counterpart recess 22 formed in the handle of the screw driver. By virtue of this construction and arrangement the oil can and screw driver are maintained securely in place and are prevented from movement when the parts are assembled. At the same time both of these articles may be readily 15 removed from the rod by unscrewing the can, in which event the screw driver will readily drop out through the opening in the rear end of the rod.
- The forward extremity of the member 9 20 of the rod is equipped with a sort of knob or enlargement 23 whereby it is adapted to receive a cloth or other suitable material 24 and forming a swab for the purpose of cleaning out the gun barrel. When this 25 swab is applied, as shown in Fig. 7, it will be retained in place on the rod when the extremity 23 is inserted in the gun barrel. The member 9 of the rod is also hollow and its forward extremity is threaded as shown 30 at 25 to receive a hollow screw 26 having a head 27 forming a seat for a relatively large washer 28 adapted to be held in place by the head 29 of a screw 30 which enters the hollow screw 25 which is interiorly threaded 35 for the purpose. This washer 28 fits closely within the barrel of the gun and is used when it is desired to oil the barrel on the inside. By moving the rod back and forth the washer distributes the oil within the 40 barrel. This washer also serves an important purpose when the rod is in use, namely, when it is located within the barrel as shown in Fig. 1. In this event the washer, by virtue of its fitting closely within the 45 barrel keeps the rod from shaking; and as the cylindrical part 13 of the rod fits closely within the rear end of the barrel, the rod is held perfectly tight within the barrel when not in use.
- 50 From the foregoing description, the use of my improved construction will be readily understood. When the barrel and body of

the gun are disconnected, as shown in Fig. 1, my improved cleaning rod 7 may be inserted in the barrel. Preparatory to such 55 insertion, the threaded parts 10 and 12 of the two rod members are disconnected, whereby the member 9 is allowed to enter the member 8, see dotted lines in Fig. 1. The members 5 and 6 of the gun may then 60 be placed in the pouch or case for transportation in the regular way, no extra space being required for the cleaning rod which, as heretofore stated, is located within the barrel. When it is desired to use the rod, it is 65 simply slipped out of the barrel by drawing it through the rear end thereof. The member 9 is then drawn out of the member 8 and the threaded parts 10 and 12 are connected, thus holding the two rod members 70 in the extended position shown in Fig. 2. The rod may then be used for swabbing or oiling the gun, as may be desired. If it is desired only to oil the gun the washer 28 is left in place and the manner of its use is 75 obvious. If it is desired to use the swab, the washer 28 is removed, together with the screws 26 and 30. The swab 24 is then applied to the knob extremity of the rod and used as heretofore explained.

Having thus described my invention, what I claim is:

A combination cleaning rod for guns adapted to be received in the barrel of the gun and composed of two telescoping members, one of the said members having an integrally formed, and enlarged, gradually tapering handle portion, open to form a receptacle for the housing of implements, and an oil can threaded into the handle portion 90 to form a closure for the receptacle, the rear extremity of the can having a protruding head of greater circumference than the rear extremity of the handle portion of the telescoping member, to closely fit the annular 95 shoulder formed on the shell chamber of the gun, for the purpose set forth.

In testimony whereof I affix my signature in presence of two witnesses.

DEAN W. KING.
